FAUCET SEAL

John L. Chaney, % John L. Chaney Instrument Co.,
Lake Geneva, Wis.

Filed Aug. 8, 1960, Ser. No. 61,665

Term of patent 14 years

(Cl. D91—3)

FIG. 1 is an elevational view of the faucet seal showing my design;

FIG. 2 is a top plan view thereof;

FIG. 3 is a section taken generally along the line 3—3 of FIG. 1.

I claim:

The ornamental design for a faucet seal, substantially as shown.
